CLAIM

The ornamental design for a offset T-shaped handle for surgical tools, as shown and described herein.

DESCRIPTION

FIG. 1 is top, front, right-side perspective view of an offset t-shaped handle for surgical tools showing the new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines in the drawings are included to show portions of the article that form no part of the claimed design.

1 Claim, 3 Drawing Sheets
